UNITED STATES PATENT OFFICE.

STANTON C. HOOPER AND GEORGE H. CLARK, OF WASHINGTON, DISTRICT OF COLUMBIA.

RADIO-RECEIVING ANTENNA.

1,379,262.

Specification of Letters Patent. Patented May 24, 1921.

Application filed September 16, 1919. Serial No. 324,228.

To all whom it may concern:

Be it known that we, STANTON C. HOOPER and GEORGE H. CLARK, citizens of the United States, residing at Washington, in the District of Columbia, have invented an Improvement in Radio-Receiving Antennæ, of which the following is a specification.

The present invention relates to radio receiving antennæ and particularly to a multiple antennæ system having for its purpose the efficient reception of long distance radio telegraphic and telephonic communications.

Heretofore it has been proposed to utilize a plurality of antennæ spaced a distance apart so that the incoming electro-magnetic waves impinge thereon at different phases, the energies of the various antennæ being collected through the agency of a series of tuning inductances associated with a radio 20 signaling receiving apparatus.

Great difficulty has been encountered in attempting to connect the radio signal receiving apparatus to a number of separate electro-magnetic wave collecting systems or 25 antennæ. This difficulty is due to the inherent capacity existing between the ground and the connecting wires joining the wave collecting systems with the radio signal receiving apparatus.

30 The object of the present invention is to obviate the difficulties above enumerated and to provide means for greatly increasing the audibility or intensity of signals received when employing a plurality of associated 35 antennæ.

Our invention will be more fully understood by referring to the annexed drawings which accompany and form a part of this specification and in which like characters of 40 reference have been used to indicate similar parts throughout the several drawings.

Figure 1 illustrates diagrammatically the arrangement of the multiple antennæ conductively connected at their elevated extremities and individually grounded.

Fig. 2 shows a plurality of antennæ as illustrated in Fig. 1 but conductively connected at both the elevated and lower extremities.

50 With particular reference to Fig. 1, numerals 1, 2, 3 and 4 are applied to individual elevated electro-magnetic wave collecting systems or antennæ having tuning inductances 5, 6, 7 and 8 together with variable condensers 9, 10, 11 and 12 inserted in

each antenna circuit and connected to the ground 13. The elevated antennæ are conductively connected as indicated at 14. We desire to point out that in this conductive connection of the individual antennæ resides the successful and efficient operation of the multiple antennæ system as an electro-magnetic wave collector. Standard radio signal responsive apparatus is connected to the tuned secondary circuit 15 inductively associated with primary inductance 8 positioned in the antennæ system 4. Fig. 2 illustrates a modification of the radio signal receiving system shown in Fig. 1, wherein the antennæ are conductively connected at the lower as well as at the elevated extremities. The conductor 16 is employed to conductively connect the antennæ system in lieu of earth connection as in Fig. 1.

In the operation of the antennæ system the individual antennæ 1, 2, 3, and 4 are spaced preferably a half wave length apart with respect to the incoming signal and in line with the general direction of propagation of the wave front of such signal transmitted from the distant radio station. The individual antennæ are separately tuned to resonance with the wave to be received by means of the variable condensers 9, 10, 11 and 12 and the accumulative effect of the energies received by the multiple antennæ integrated in the radio receiving circuit 15, thereby actuating apparatus capable of translating the received energy into intelligent signals.

Having thus described our invention, what we claim and desire to secure by Letters Patent of the United States is:

1. In a radio telegraphic and telephonic receiving system, the combination of a plurality of antennæ located at approximately equal distances apart on a line bearing in the direction of the distant transmitting station, means for tuning to resonance each antenna to the incoming wave length and a conductive connection joining the elevated extremities of said antennæ, the lower extremities of which are grounded and means for integrating the increments of energy collected by the individual antennæ in a receiving apparatus substantially as described.

2. In a radio telegraphic and telephonic receiving system the combination of a plurality of antennæ located at approximately equal distances apart on a line bearing in the direction of the distant transmitting sta-

tion, means for tuning to resonance each antenna to the incoming wave length and a conductive connection joining the elevated extremities of said antennæ and a second conductive connection joining the lower extremities of the antennæ and a receiving apparatus inductively associated with one of said antennæ substantially as and for the purpose described.

3. In a radio telegraphic and telephonic receiving system the combination of a plurality of antennæ located at approximately a half wave length apart with respect to the incoming signal on a line bearing in the direction of propagation of the wave front of such signal, means for tuning to resonance each antenna to the incoming signal, and means for connecting said antennæ to

minimize the loss due to the capacity effect to ground substantially as described.

In testimony whereof I, STANTON C. HOOPER, have signed my name to this specification in the presence of two subscribing witnesses, this 11th day of September, 1919.

STANTON C. HOOPER.
